LAST

Original Filed April 21, 1924

Patented May 12, 1925.

1,537,621

UNITED STATES PATENT OFFICE.

CLINTON M. SEARL, OF PORTSMOUTH, OHIO, ASSIGNOR TO THE VULCAN LAST COMPANY, OF PORTSMOUTH, OHIO, A CORPORATION OF OHIO.

LAST.

Original application filed April 21, 1924, Serial No. 707,796. Divided and this application filed November 24, 1924. Serial No. 751,759.

To all whom it may concern:

Be it known that I, CLINTON M. SEARL, a citizen of the United States, residing at Portsmouth, in the county of Scioto and

5 State of Ohio, have invented certain new and useful Improvements in Lasts, of which the following is a specification, reference being had therein to the accompanying drawing.

10 My invention relates to an improvement in lasts, and is particularly directed to lasts of the divided type—that is to say, to that type of last which is divided into two parts, a toe part and a heel part, movable relatively to each other to collapsed and extended positions. The present application is a division of my application filed April 21, 1924, Serial No. 707,796.

15 It is desirable in lasts of this type that the last be capable of being easily collapsed so that it may be removed from a shoe without injury to the lining of the shoe and without stretching the shoe out of place.

20 In lasting a shoe the last is held upside down—that is, with the sole side uppermost—and inasmuch as a great deal of pressure is put on the toe of the last during the lasting operation, this tends to collapse the last, and consequently one of the objects of 25 my invention is the provision of a construction in which the last is capable of withstanding the stresses to which it is subjected during the lasting operation without collapsing, but may be readily collapsed by the 30 operator when desired.

35 In one form of last now in extensive use, the fore part and heel part are attached to each other by a link attached to the fore part and heel part by pins so located relatively that a line drawn through their centers will fall above the axis on which the last parts move when the last is collapsed and below this point or axis when the last is extended.

40 In such a construction, the greater the distance the pins are below the axis of the last when the last is extended, or the greater the distance they are above the axis of the last when the last is collapsed, the more resistance the last will offer to collapse or extension, but this distance is limited inasmuch as the pins must be located in the last body itself, and in the case of wooden lasts the pins must be kept at an appreciable dis-

55 tance from the bottom or sole face owing to the danger of splitting the last when the same is in use or when being moved from extended position to collapsed position or vice versa.

60 In the present construction I have provided an arrangement for attaching the two last parts to each other whereby an effect is obtained which is as efficient as the lowering of the pins in the above-outlined construction to the danger point, the resistance 65 to collapse or extension offered by my last being very materially increased, without, however, necessitating placing of any pins at a point where they are likely to cause the 70 last to split.

75 It is one of the especial objects of my invention to provide a last in which the last parts are held together under tension and not simply held in expanded or collapsed position under tension.

80 It is a further object of my invention to hold the last parts together by means employing a lever, with the parts constantly under tension.

85 It is a still further object of my invention to hold the parts of the last together under tension with the parts so arranged that the tension will assume its maximum when the parts are either in their fully expanded or fully collapsed position.

90 It is an additional object of my invention to provide the holding together of the parts under tension and to associate therewith a lever, the parts being so arranged that the tension will achieve its maximum at the completely expanded or collapsed position 95 of the last parts. It will be realized that the tension may be created by a variety of means which may be very compressible or expandable, and that the details of creating this condition are not essential.

100 It is a further object of my invention to provide such mechanism to hold the parts of the last together under tension that it will not be necessary to have resilient links or resilient anchor pins. Such means are eliminated and the same results are obtained.

105 It is a further object of my invention to provide the holding of such parts together under tension and the increasing of this tension at extreme positions together with means to lock the parts in extended position by such tension means to resist the pressure,

tending to collapse the last imposed on the bottom of the toe member in constructing the shoe thereon until such tension means is overcome by the operator breaking the last.

5 In the accompanying drawing I have shown a sectional view illustrating my invention.

Referring to the drawing, I here provide a last comprising a heel part 1 and a toe part 2, divided by an arcuate cut 3. The last of this figure is provided with a bearing pin 4 at the center of the arc 3. A toggle comprising the two links 5 and 6 ties the two last parts together, one end of the link 5 being attached to the heel part by a pin 7, the other end of this link being mounted on the bearing or fulcrum 4. The other link 6, which is located in the last toe, has one end attached to the toe part 2 by a pin 8, the other end being mounted on the bearing pin 4. The pins 7 and 8 are so disposed that a line drawn through their centers falls below the bearing pin or fulcrum 4 when the last parts are extended and above the bearing pin when the last is collapsed.

To hold the last parts under tension in either collapsed or extended position, I provide a curved link 9 having its heel end pivoting on the pin 7, the other end of this link or lever extending into the toe part of the last, where it receives a pin 10 by which this end of the link is pivotally attached to another link or lever 11, pivotally attached to the lever 6 of the toggle by a pin 12 located intermediate the two ends of the toggle and in such a position that a line drawn through its center and the center of the pin 7 will fall below the center of the bearing pin or fulcrum 4 when the last is extended and above this pin when the last is collapsed. Likewise the centers of the pins 7 and 8 and 7 and 10 will fall below the center of the pin 4 at the same time. Power is applied to the toe end of the lever 9 by a spring 13 held under compression by a pin 14 passing transversely of the last into the last toe.

In this form of my invention it will be seen that power is applied to the toggle intermediate the ends thereof through the medium of the spring 13 and the levers or links 9 and 11.

In operation with the last extended, it will be seen that the last parts are held in this position under tension by the spring 13, this spring pressing downwardly on the end of the lever 9, this force being transmitted to the toggle link 6 in a direction to tend to force the toggle link 6 toward the bearing pin or fulcrum 4. In other words, the point 55 or pin 10 is tending to move downwardly to approach the pin 8; likewise the pin 7 is being forced by the spring 13 through the link 9 to approach the pin 8. Consequently the two last parts are forced toward each other 60 to hold them in extended position. In col-

lapsed position the centers of the pins 7, 8, 10 and 12 lie above the center of the pin 4, so that the spring 13 will cause the last parts to be drawn toward each other to hold the last collapsed under tension.

70 In this embodiment of my invention it will be seen, therefore, that the lever arm to which force is applied by the spring 13 and represented by the distance between the lines a and b , is of its greatest length when the last parts are in extended position, and consequently the last parts will be held under greatest tension when the last is extended. The same thing is true when the last parts are collapsed.

80 It will be apparent that I have provided a last structure wherein the last parts are held in extended position and in collapsed position under tension, thereby providing a structure which will successfully withstand 85 accidental collapse or extension of the last parts when the same are in use in the manufacture of shoes. It will be seen also that in my invention I provide a structure in which the force exerted on the last parts to hold 90 the last in extended and in collapsed position is of some magnitude, my improved construction being such, however, that this increase in force is provided without weakening the last. In other words, more power is available 95 for holding the last parts in adjusted position due to my improved structure than is possible in lasts as now manufactured.

100 It will be seen also that I have provided a last structure wherein the last parts are held in extended position and in collapsed position under greatest tension. In other words, the tension under which the last parts are held to each other when the last is extended or when the last is collapsed, as the case may 105 be, is greater than the tension under which the last parts are held when in an intermediate position.

Having thus fully described my invention, what I claim as new and desire to secure by 110 Letters Patent is:

1. In a last of the divided type and comprising a toe part and a heel part, a bearing pin for said last parts, a link having one end attached to the heel part and its other end mounted on such bearing pin, a second link having one end attached to the toe part and its other end mounted on said bearing pin, and means for applying power to said links in a direction to shorten the distance between 115 the points of attachment of said links to the last parts to thereby hold the last parts in extended position and in collapsed position.

120 2. In a last of the divided type and comprising a toe part and a heel part, a bearing pin for said last parts, a link having one end attached to the heel part and its other end mounted on said bearing pin, a second link having one end attached to the toe part and its other end mounted on said bearing pin, a 125

third link having one end pivoted to said second link intermediate the ends thereof, and a fourth link having one end pivoted to the end of the third link and its other end pivoted to the end of the first link at the point of attachment of the first link to the heel part, and a spring for applying power to the point of attachment of the third and

fourth links to each other to shorten the distance between the points of attachment of the first and second links to the last parts whereby the last parts will be held in extended position and in collapsed position under tension.

In testimony whereof, I affix my signature.
CLINTON M. SEARL.
